UNITED STATES PATENT OFFICE.

ROBERT R. JOHNSON, OF ATLANTA, GEORGIA.

ASH-SIFTER.

1,217,314.

Specification of Letters Patent.

Patented Feb. 27, 1917.

Application filed October 2, 1915, Serial No. 53,800. Renewed January 17, 1917. Serial No. 142,966.

To all whom it may concern:

Be it known that I, ROBERT R. JOHNSON, a citizen of the United States, residing at Atlanta, in the county of Fulton and State 5 of Georgia, have invented new and useful Improvements in Ash-Sifters, of which the following is a specification.

The invention contemplates the provision of a combined shovel and ash sifter, designed 10 to permit of the ashes to be sifted in the ash pit of a stove, furnace, or the like, during which time the draft through the stove or furnace will carry off the dust through the chimney, and thereby prevent the same from 15 entering the room.

In carrying out my invention I aim to provide a novel construction of a device of the above mentioned character, embodying among other features a sifter screen pivotally supported in spaced relation above the 20 bottom of the shovel, with means for operating the same, whereby the unconsumed particles of fuel remaining upon the screen subsequent to the sifting operation, can be 25 readily delivered into the stove, while the ashes and other refuse supported upon the shovel proper may be then distributed into a suitable receptacle.

Other objects will appear as the nature of 30 the invention is better understood, the same residing in the combination, construction and arrangements of parts hereinafter more fully described.

In the drawings forming part of this application, like numerals of reference indicate 35 similar parts in the several views and wherein:

Figure 1 is a top plan view of the device constructed in accordance with my invention.

Fig. 2 is a side elevation.

Fig. 3 is a longitudinal sectional view taken on lines $a-a$ of Fig. 1.

Fig. 4 is a bottom plan view.

Fig. 5 is a detail perspective of the sifter screen.

Fig. 6 is a similar view of the pivoted plate for controlling the discharge opening at the end of the shovel.

Referring more particularly to the drawings A indicates generally a shovel of usual 50 formation, constructed from sheet metal and comprising a bottom 5, side walls 6, a rear end wall 7, and a handle 8, the latter being 55 preferably hollow.

Pivottally mounted between the side walls

6 of the shovel in spaced relation above the bottom 5 thereof is a sifter screen, which may be constructed from any suitable material and of any desired formation, but as 60 shown in this embodiment of the invention comprises a frame 9 constructed from a single length of wire and outlined similar to the bottom 5, the parallel side members 10 of which are connected adjacent their forward 65 ends by the cross piece 11 as shown. The frame is covered by a sheet of foraminous material 12 which may be of any desired mesh. The forward ends of the parallel side members 10 of the frame are formed to provide 70 trunnions 13 which are journaled in the side walls 6 of the shovel a suitable distance above the bottom 5, while the opposite end of the frame is supported upon inwardly projecting lugs 14 formed from the side wall 75 6 adjacent the rear wall 7, to maintain the sifter screen in its entirety spaced equidistantly from the bottom 5. One of the trunnions 13 is extended to provide a crank 15 with which one end of a reciprocating element 16 is connected for the purpose of 80 operating the sifter in a manner to be presently described, the element 16 comprising a single length of wire disposed exteriorly of the shovel and extending throughout the entire 85 length thereof, being bent inwardly as at 17 to enter the hollow handle through a suitable opening 18 in the under side thereof, the element having a portion disposed within the handle, while the opposite end thereof 90 projects outwardly through an elongated slot 19 and terminates to provide a loop 20 adapted to be engaged by the finger to reciprocate the element for the purpose hereinabove stated.

Arranged at the forward end of the sifter screen is a plate 21 normally closing the space between the sifter screen and the bottom 5 of the shovel, the upper edge of the plate being formed with spaced eyes 22 95 loosely embracing the cross piece 11 of the sifter, whereby the plate is mounted for swinging movement.

As above stated, the device is designed to 100 permit the ashes to be sifted within the ash pit of a stove, furnace or the like, and that consequently the handle 8 may be of suitable length to permit of this use. The unsifted ashes are directed upon the sifter screen by means of the plate 21 and sifted by imparting 105 to the shovel a reciprocatory motion in the usual well known manner. During this 110

sifting operation the finer particles of ashes will pass through the foraminous material upon the bottom 5 of the shovel, while the unconsumed particles of coal will remain 5 upon the sifter screen. Subsequent to the sifting operation, the sifter screen is adapted to be elevated through the medium of the reciprocating element 16 in the manner shown in the drawings, with a view of re- 10 turning the unconsumed particles of coal into the fire box of the stove, furnace or the like. The slot 19 is of such length, to permit the loop 20 to engage the end wall thereof to limit the upward movement of 15 the sifter screen whereby the latter upon release of the finger from the manipulating loop 20, will gravitate to normal position. Subsequent to delivering the unconsumed coal into the fire box of the stove or the like, 20 an hereinabove stated, the shovel is then intended to be disposed in a vertical position to permit the ashes and other refuse supported upon the bottom 5 of the shovel to be distributed into a suitable receptacle, 25 it being manifest that the weight of the ashes will lift the plate 21 to permit of their discharge into the receptacle, after which the plate will gravitate to normal position thereby closing the opening between the 30 upper edge of the sifter screen and the bottom 5 of the shovel.

It is believed that from the foregoing description the nature and advantages of the invention will be thoroughly understood 35 without requiring a more extended explanation and therefore the same has been omitted. However I desire to have it understood that I do not limit myself to the precise construction herein illustrated and de- 40 scribed, as various changes may be resorted to when desired, especially with regard to the formation and dimensions of the various parts, as fall within the scope of the appended claims without departing from the 45 spirit of the invention.

What is claimed is:—

1. The combination with a shovel comprising a bottom and side walls, a sifter screen spaced above the bottom and pivotally mounted between the side walls adjacent the forward ends thereof, lugs projecting inwardly from the side walls adjacent the opposite ends thereof and adapted to support the free end of said sifter in spaced relation to the bottom of the shovel, a swingingly mounted plate normally closing the opening between the forward edge of the sifter and said bottom, and a reciprocating element connected with said sifter for operating the latter. 50

2. The combination with a shovel comprising a handle, a bottom and side walls, of a sifter screen spaced above the bottom and pivotally mounted between said side walls adjacent the forward ends thereof, a recip- 55

rocating element disposed at one side of the shovel and having one end connected with the pivot of the sifter, said element having a portion disposed within the handle, and its free end projecting therefrom through an elongated slot therein, and formed to provide a manipulating loop, said loop being adapted to engage one end wall of said slot to limit the movement of said element in one direction, and a swingingly mounted plate at the forward end of the shovel for normally closing the opening between said sifter and the bottom of the shovel. 70

3. The combination with a shovel, of a sifting screen spaced above the bottom thereof and pivotally associated therewith adjacent its forward end, a plate swingingly supported upon the forward edge of the sifter and normally closing the opening therebetween and the bottom of the shovel, means for raising said sifter independently of the plate, and means for limiting the upward movement of the sifter whereby the latter will gravitate to normal position upon release of said means. 80

4. The combination with a shovel, of a sifter screen spaced above the bottom thereof and including a frame, and a sheet of foraminated material covering the latter, the side members of the frame being pivotally associated with the shovel adjacent its forward end, one of said members terminating in a crank, a reciprocating element having one end connected with the crank and its opposite end associated with the handle of the shovel for operating said sifter, and a plate mounted on the forward end of the sifter for independent swinging movement, said plate normally closing the opening between the forward edge of the sifter and bottom of the shovel. 95

5. The combination with a shovel, of a sifting element normally disposed in spaced relation above the bottom of the shovel, and adapted to initially receive and support thereon the unsifted material, said element being pivotally connected with the forward end of the shovel, and means for tilting said element subsequent to the sifting operation to discharge the larger particles of said material therefrom. 100

6. The combination with a shovel, of a sifting element normally disposed in spaced relation above the bottom of said shovel, and adapted to initially receive and support thereon the unsifted material, said element being pivotally connected with the forward end of the shovel, means for tilting said element in the direction of the forward end of the shovel subsequent to the sifting operation to discharge therefrom the larger particles of the said material, and means for limiting the adjustment of said element. 105

7. The combination with a shovel, of a

sifting element pivotally connected with the side walls thereof adjacent their forward ends, said element being disposed above the bottom and below the upper edges of said 5 side walls, means controlling the opening between the forward edge of the sifter and the bottom of the shovel, and adapted when in normal position to direct the unsifted material upon said element, means for reciprocating the device to sift the material through said element upon the shovel, and said first mentioned means being free to automatically assume an inoperative position to permit the sifted material to be discharged from 10 the shovel through said opening.

8. The combination with a shovel, of a sifting element pivotally connected with the side walls thereof adjacent their forward ends, said element being disposed above the 20 bottom of the shovel and below the upper

edges of said side walls, means for controlling the opening between the forward edge of the sifter and the bottom of the shovel and adapted when in normal position to direct the unsifted material upon said sifter, 25 means for tilting the sifter toward the forward end of the shovel subsequent to the sifting operation to discharge therefrom the larger particles of the material, and said first mentioned means being freely supported 30 to gravitate to inoperative position to permit the sifted material to be discharged from the shovel through said opening.

In testimony whereof I affix my signature in presence of two witnesses.

ROBERT R. JOHNSON.
